UNITED STATES PATENT OFFICE.

EINAR OLAUS IVERSEN, OF CHICAGO, ILLINOIS.

DOOR-HOLDER.

1,159,036.

Specification of Letters Patent.

Patented Nov. 2, 1915.

Application filed April 7, 1915. Serial No. 19,647.

To all whom it may concern:

Be it known that I, EINAR OLAUS IVERSEN, a citizen of the United States, and a resident of the city of Chicago, county of Cook, and State of Illinois, have invented 5 certain new and useful Improvements in Door-Holders, of which the following is a specification.

My present invention relates to door 10 holders, and has special reference to the provision of an extremely simple device for steadyng and holding a door, after the same has been unlatched, at any desired angle with the door casing.

15 A peculiar advantage of my device is that after the device has been set to hold the door in the desired position, the door may then be swung farther open or closed, but when it is brought back to the desired position it will be again engaged by the door 20 holder without any necessity of further manipulation or adjustment thereof.

I obtain the above objects by means of the structure illustrated in the accompanying drawing, in which:

Figure 1 is a perspective of my invention; and Fig. 2 is a plan, illustrating in dotted lines how a door will be engaged thereby.

My invention comprises a casting of substantially V-shaped plan, the arms 5 and 6 whereof are preferably at right angles to each other.

The casting at the intersection of the arms of the V is filled out at 7, both for the purpose of rendering the central portion of the casting heavier than the wings, and also for forming a face of sufficient width to abut the edge of a door to be engaged thereby.

40 I provide upon the top of the meeting edge of the arms a sphere, or knob 8, of ornamental design, and for the additional purpose of adding weight at this point.

The bottom edge of the casting, which lies 45 adjacent the floor, is adapted to contact the floor at three points, namely A, B, and C. The point A being directly under the corner formed by the meeting of the arms 5 and 6, and the points B and C being under the extreme outer ends of the arms 5 and 6, respectively.

When it becomes desirable to hold a door

open at an angle with the door casing, the door is first opened to the desired position, and the casting or weight is placed upon 55 the floor adjacent the outer edge of the door (Fig. 2) the face 7 thereof contacting the front edge of the door, and the arms 5 and 6 extending on either side thereof, as shown in full lines in Fig. 2, and due to the weight 60 of the casting, the door will be held in this position.

When the door is to be closed, or opened wider than the position just described, the weight, being the heaviest at the point A, 65 will pivot at that point and the door will, as shown in dotted lines in Fig. 2, pass the arm unobstructed, remaining in this position so that when the door is brought back to its first position, it will strike the arm 70 extending into its path and cause the casting to pivot again at A back to its initial position.

What I claim is,—

1. A door holder comprising an angular 75 shaped member the respective arms of which are disposed in vertical planes and the meeting portion of which is adapted to engage the outer edge of a door and lie adjacent the same, the bottom edge of said 80 member contacting the floor at three separate points.

2. A door holder comprising an angular shaped member, the respective arms of which are at an angle to each other, the 85 meeting portion of said arms being adapted to engage the outer edge of a door and to abut and lie adjacent the same, the bottom edge of said member being irregular in outline and adapted to contact the floor only at 90 a point at the junction of said arms and at a point under the outer extending ends of each respective arm.

3. A door holder comprising an angular shaped member the respective arms of 95 which are disposed in vertical planes at an angle with each other and the meeting portion of which is adapted to engage the outer edge of a door and to abut and lie adjacent the same, and the bottom edge of said member contacting the floor only at a point at 100 the junction of said arms, and at a point under the outer extending ends of each respective arm.

4. A door holder comprising a central portion having a triangular horizontal section the base of which section is adapted to contact the edge of a door, and lateral members extending from the legs of the triangular section into the arc of rotation of the door whereby the movement of the door will cause the rotation of the member and the

inclusion of the door between the lateral extensions thereof.

Signed at Chicago, Cook county, Illinois,
this 19 day of March, 1915.

EINAR OLAUS IVERSEN.
